US00D694406S

(12) **United States Design Patent**
Hahn et al.

(10) **Patent No.:** **US D694,406 S**
(45) **Date of Patent:** **** Nov. 26, 2013**

(54) **TOOL SHIELD**

- (71) Applicant: **Blue Belt Technologies, LLC**,
Pittsburgh, PA (US)
- (72) Inventors: **Adam Hahn**, Pittsburgh, PA (US);
Benjamin Oliver McCandless,
Pittsburgh, PA (US)
- (73) Assignee: **Blue Belt Technologies, LLC**,
Pittsburgh, PA (US)

(**) Term: **14 Years**

(21) Appl. No.: **29/451,357**

(22) Filed: **Apr. 1, 2013**

Related U.S. Application Data

- (62) Division of application No. 29/349,737, filed on Apr. 28, 2010, now Pat. No. Des. 679,811.

(57) **CLAIM**

The ornamental design for a tool shield, as shown and described.

DESCRIPTION

FIG. 1 is a right and top side perspective view of a tool shield showing my new design;

FIG. 2 is a left plan view of the tool shield of FIG. 1;

FIG. 3 is a right plan view of the tool shield of FIG. 1;

FIG. 4 is a top plan view of the tool shield of FIG. 1;

FIG. 5 is a front end view of the tool shield of FIG. 2; and,

FIG. 6 is a rear end view of the tool shield of FIG. 1.

The broken line showing is for environmental purposes only and forms no part of the claimed design.

1 Claim, 3 Drawing Sheets

UNITED STATES PATENT AND TRADEMARK OFFICE
CERTIFICATE OF CORRECTION

PATENT NO. : D694,406 S
APPLICATION NO. : 29/451357
DATED : November 26, 2013
INVENTOR(S) : Hahn et al.

Page 1 of 1

It is certified that error appears in the above-identified patent and that said Letters Patent is hereby corrected as shown below:

Title Page, in column 2, under "(57) Claim", line 1, delete "shield," and insert --shield--, therefor

Title Page, in column 2, under "(57) Claim", line 2, after "described.¶", insert --CLAIM OF PRIORITY¶ This patent application claims the benefit of priority to United States Patent Application Serial No. 29/349,737, filed April 28, 2010, which is hereby incorporated herein by reference in its entirety.¶--, therefor

Title Page, in column 2, under "Description", line 6, after "and", delete ":", therefor

On Title Page 2, in column 1, under "U.S. Patent Documents", line 9, delete "DeJuan, Jr. et al." and insert --Dejuan, Jr., Eugene, et al.--, therefor

Signed and Sealed this
Twentieth Day of January, 2015

Michelle K. Lee
Deputy Director of the United States Patent and Trademark Office
